UNITED STATES PATENT OFFICE.

ERNEST R. HILL, OF WILKINSBURG, PENNSYLVANIA, ASSIGNOR TO THE WESTINGHOUSE ELECTRIC AND MANUFACTURING COMPANY, OF PENNSYLVANIA.

CAR OR TRAIN LIGHTING SYSTEM FOR ELECTRIC RAILWAYS.

SPECIFICATION forming part of Letters Patent No. 633,971, dated September 26, 1899.

Application filed April 14, 1899. Serial No. 713,016. (No model.)

To all whom it may concern:

Be it known that I, ERNEST R. HILL, a citizen of the United States, residing at Wilkinsburg, in the county of Allegheny and State 5 of Pennsylvania, have invented a new and useful Improvement in Car or Train Lighting Systems for Electric Railways, (Case No. 823,) of which the following is a specification.

My invention relates to electric railways 10 and particularly to railways operated by systems which embody positive, negative, and neutral contact-conductors, between two of which the motor or motors and the electric lights are connected.

15 In three-wire electric-railway systems the positive and negative contact-conductors are usually arranged either in alternating sections or continuously along parallel or substantially parallel lines of track, and in order 20 to avoid short circuits it is essential that the current-collecting devices shall not bridge the space between adjacent conductors of opposite sign in the one case or the conductors of opposite sign in passing from one track to 25 the other in the other case. The momentum of the car or train may be depended upon to carry the current-collecting devices over from one contact-conductor to the next, and thus avoid any considerable disarrangement or dis- 30 comfort by reason of the interruption of the supply of current to the motor or motors. In the case of lamps employed for lighting the car or train, however, such interruption of the current is decidedly objectionable.

35 The object of my present invention is to provide a system and combination of circuits by means of which the car or train may pass from a positive to a negative conductor, or vice versa, without cutting off the illumination or power and at the same time avoiding the establishment of a short circuit.

In the accompanying drawings, Figure 1 is a diagram of a three-wire railway system constructed and arranged in accordance with my 45 invention; and Fig. 2 is a similar view of a modified arrangement of circuits.

Reference being had to Fig. 1, 1 and 2 are direct-current generators which may be of the usual type employed in railway work, 50 they being connected in series, as is usual in

three-wire systems. The positive feeder 3 is connected to sectional contact-conductors 4, extending along the line of the railway, and the negative line-feeder 5 is connected to sectional contact-conductors 6, which alternate with the positive contact-conductors 4. I have represented each of the contact-conductors 4 and 6 by means of a line that is partially dotted in order to indicate that these conductors are of much greater length 55 than it is possible to indicate by the actual length of the lines in the drawings, they being in practice many times the length of the spaces between the adjacent ends of the sections. The neutral conductor 7 may be continuous and connected between the two generators 1 and 2. This neutral conductor is here indicated as the track-rails, it being understood that such rails will be connected and bonded so as to make a good conducting- 60 path for the current. A contact-conductor separate and independent from the track-rails may be employed for this purpose, if desired, but ordinarily the rails, suitably connected and bonded, will serve the purpose 65 70 75 equally well and at a less expense.

The car is represented by two wheels 8 and 9 resting upon the track 7 and propelled by one or more electric motors, two of such motors 10 and 11 being here indicated. Two 80 sets or series of lamps 12 and 13 are also shown for illuminating the car.

The current-collecting apparatus comprises two contact-shoes 14, electrically connected so as to constitute, in effect, a single contact 85 device, and two shoes 15, connected together in the same manner so as to constitute, in effect, another single contact device. The contact-shoes 14 span a space of less length than the distance between adjacent conductors 4 90 and 6, and shoes 15 also span a space of less length than the distance between the adjacent ends of adjoining conductors 4 and 6. The two pairs of shoes, however, overlap in position, so that the rear shoe does not leave its 95 contact-conductor until the forward shoe makes contact with the next contact-conductor of opposite sign. The shoes 14 are connected to one terminal of the motor 10 and one terminal of the lamp-circuit 12, and 100

the shoes 15 are connected to the one terminal of the motor 11 and one terminal of the lamp-circuit 13. The other terminals of both motors and both lamp-circuits are connected 5 through the wheels of the car to the track or neutral conductor 7.

It will be understood from the foregoing and the known structural and operative conditions pertaining to three-wire systems of 10 distribution that the difference of potential between the neutral conductor and each of the other feeding-conductors is one-half that between the positive and negative conductors.

15 It will be seen that when both pairs of shoes 14 and 15 are in contact with the same contact-conductor, whether the same be positive or negative, both motors and both sets of lamps will be supplied with current at a 20 pressure equal to one-half the potential between the feeders 3 and 5.

When the car is in the position shown in the drawings, only the motor 10 and lamps 12 will be supplied with current, and at the 25 next step, when the outside shoe 15 comes into contact with the conductor 4, assuming that the car is moving from right to left, the rear shoe 14 will leave the conductor 6, and only the motor 11 and lamps 13 will then be 30 in circuit until both the forward shoes 14 and 15 come into engagement with the contact-conductor 4. It follows, therefore, that during the greater portion of the time both sets of lamps will be in circuit and that during 35 short periods only one of the sets will be in circuit. While this arrangement is not such as to provide an absolutely uniform illumination, yet with a proper number of lamps in each set the flicker in passing from one contact-conductor to another will be so small as 40 to produce no serious discomfort.

Referring now to Fig. 2, I have shown the generators 1 and 2 as respectively connected by means of their outside terminals to continuous contact-conductors 3^a and 5^a, these being severally arranged along separate lines of track. These separate tracks or lines of track 7^a and 7^b are connected together in parallel at numerous points and at one end are 45 connected to a point between the two generators, thus constituting, in effect, a single neutral conductor. As here shown, these neutral conductors are the track-rails, it being understood that they are suitably connected 50 and bonded to provide a good conducting-path for the current for operating the vehicles running over the same. Where two or more lines of track are arranged substantially as indicated in this figure of the drawings, it is usually 55 necessary to provide suitable switches and crossovers to enable cars to pass from one track to another. I have illustrated such an arrangement in this figure, the crossover track being indicated at 7^c. In order to provide 60 the motors and lights with current while passing from one track to the other, the positive conductor 3^a is provided with an exten-

sion 4^a, parallel to the track 7^c, and the conductor 5^a is provided with a similar extension 6^a, also parallel to the tracks 7^c. A space is 70 left between the ends of the extensions 4^a and 6^a, and this space is made sufficient with reference to the distance spanned by the shoes 14 and 15, as already described in connection with Fig. 1, so that there will be no short 75 circuit established, but so that the one or the other of the sets of lamps 12 and 13 will be always supplied with current. The single car and equipment shown in connection with this figure are the same as those shown in 80 connection with Fig. 1, except that only a single motor 10 is here indicated, the shoes 15 being here employed solely as the terminal of the lamp-circuit 13.

It will be understood that any desired number of motors per car may be employed in order to provide the desired propelling power and a proper distribution of the weight, and also that my invention may be utilized in connection with either a single car or a train 90 of cars.

Assuming that a train of cars is employed, two of which—one at the front and the other at the rear, for example—are equipped with motors, each of the motor-cars may be provided with two shoes, as indicated in the drawings, and each car of the train be provided with two sets of lamps, one of such sets being connected to one pair of contact-shoes and the other set to the other pair. 100 The lamps for the entire train may be supplied from either motor-car, or, if desired, one half may be supplied from one motor-car and the other half from the other.

In case a train is provided with two motor-cars it is within my invention to employ only one contact-shoe or one pair of electrically-connected shoes for each of said cars and two lamp-circuits for the entire train, one terminal of one lamp-circuit being connected to 110 one shoe and one terminal of the other circuit to the other shoe. With this arrangement it is obvious that one or both of the sets of lamps will always be in circuit with the source of current. I have shown such an arrangement on the upper track in Fig. 2.

It will also be understood that the lighting system here illustrated and described may be employed in connection with cars or trains that are propelled otherwise than by electric 120 motors, if desired.

In the propulsion of a car or a train by a plurality of electric motors supplied either severally or in pairs or sets through separate current-collecting devices which collectively 125 span a greater space than that between adjacent ends of contact-conductors, as indicated in the drawings, the car or train is obviously at all times subjected to the propelling force of at least one motor, except when the circuit 130 is broken at the controller. This insures greater economy and smoothness of operation than is possible where the motors are all periodically cut out of circuit as the current-col-

lectors pass from section to section of the contact-conductor.

I claim as my invention—

1. In a lighting system for railway-vehicles embodying positive, negative and neutral contact-conductors, a car or train provided with two current-collecting devices arranged to severally engage one or both of the positive and negative contact-conductors, and two sets of lamps severally connected between the respective collecting devices and the neutral conductor.
2. In a lighting system for railway-vehicles embodying positive, negative and neutral conductors, a motor-car provided with means for connecting its motor or motors at certain times between a positive and a neutral conductor and at other times between a neutral and a negative conductor, in combination with two independent sets of lamps, at least one of which is at all times in circuit either between the positive and the neutral conductor or between the neutral and the negative conductor.
3. In a lighting system for railway-vehicles embodying continuous neutral contact-conductors and interrupted positive and negative contact-conductors, a car or train having two independent current-collecting devices for making contact with the positive and negative conductors each of which spans a less space than that between adjacent ends of positive and negative conductors, but both of which combine to span a greater space than that between adjacent ends of such conductors, in combination with two independent sets of lamps respectively connected between said current-collecting devices and the neutral conductor.
4. In an electric railway embodying continuous neutral contact-conductors and in-

terrupted positive and negative contact-conductors, a car or train provided with two independent current-collecting devices which together serve to span a space of greater length than that between the ends of adjacent contact-conductors of opposite sign, said current-collecting devices constituting independent lamp-circuit terminals and at least one of them constituting a motor-circuit terminal. 45 50

5. In an electric railway embodying a continuous neutral contact-conductor and sectional positive and negative contact-conductors alternating with each other, a car provided with two independent sets of lamps 55 and with two independent, overlapping current-collecting devices one of which is always in contact with either a positive or a negative conductor but which severally span a space less than that between the ends of adjacent 60 contact-conductors, said devices constituting independent lamp-circuit terminals and at least one of these constituting a motor-circuit terminal.

6. In an electric railway embodying a continuous neutral contact-conductor and interrupted positive and negative contact-conductors, a car or train provided with a plurality of propelling-motors and a plurality of independent current-collecting devices which 70 collectively span a space of greater length than that between the adjacent ends of the interrupted conductors, the current-collecting devices severally constituting terminals for separate motor-circuits. 75

In testimony whereof I have hereunto subscribed my name this 13th day of April, 1899.
